FLOOR AND WALL JOINT

Merlin A. Wieting, 365 S. Main, Brillion, Wis.
Filed Aug. 9, 1962, Ser. No. 215,876
5 Claims. (Cl. 20—74)

This invention relates to a floor and wall joint and to a preformed corner for use therewith.

One purpose of the invention is a floor and wall joint in which a flexible floor covering, for example linoleum, extends from the floor partly up along the side wall, and which includes means for covering the upper edge of the flexible floor covering and the slits at the corners.

Another purpose is a preformed member which can be used in a floor and wall joint to cover the otherwise visible vertical edges of the flexible floor covering.

Another purpose is a simple and inexpensive preformed corner member for use in a joint of the type described.

Other purposes will appear in the ensuing specification, drawings and claims.

The invention is illustrated diagrammatically in the following drawings wherein:

FIGURE 1 is a perspective of a portion of a finished floor and wall joint,

FIGURE 2 is an enlarged top plan view illustrating one of the corners shown in FIGURE 1,

FIGURE 3 is a section along plane 3—3 of FIGURE 2,

FIGURE 4 is a section along plane 4—4 of FIGURE 2,

FIGURE 5 is a section along plane 5—5 of FIGURE 3,

FIGURE 6 is an enlarged top plan view illustrating another of the corners of FIGURE 1,

FIGURE 7 is a section along plane 7—7 of FIGURE 6,

FIGURE 8 is an enlarged top plan view of a vertical edge, as shown in FIGURE 1, and

FIGURE 9 is a section along plane 9—9 of FIGURE 8.

In FIGURE 1, a flexible floor covering 10, which may be linoleum, or any other material conventionally used as a floor covering for kitchens, bathrooms, family rooms, and the like, may cover a floor undersurface 12 and may extend partly up along walls 14. That portion of the floor covering which extends upwardly along the walls is indicated at 16 in FIGURE 1. As shown in FIGURE 3, there may be a base member 18 which extends along the joint between the floor and wall and forms a support for the floor covering at the joint. Preferably the base member 18, which may be wood or the like, has a somewhat arcuate upper surface 20 which allows the floor covering to form a smooth curve between the wall and floor.

The upper edge 22 of the floor covering may be covered or masked by a suitable border member 24, which may be a metal strip or the like and which has a front portion 26 which extends partly down the surface of the floor covering and a back portion 28 which extends a substantial distance behind the floor covering and is used to hold the upper edge of the floor covering to the wall.

As each of the corners of the room and adjacent each door, it is necessary to mask or cover the vertical edges of the floor covering. At the corners it is necessary to slit that portion of the floor covering extending upwardly along the wall in order to have a smooth joint. This slit will extend partly along the curved portion of the floor covering at the joint. In order to cover this slit I may provide a corner member 30 which is used for an outside corner or a corner member 32 which is used for an inside corner. I also provide a member 34 which is used at

2

the edge where the floor covering joins molding or the like 36.

Considering first the outside corner 30 which is illustrated in FIGURES 2—5, the corner may include a lower curved portion 38 which has the same general contour or curvature as the surface 20 of the base 18. The corner also includes a main upright portion 40 which extends vertically upward along the wall surface. The main portion 40 may include a pair of side walls 42 and 44 which 5 may form an angle other than 90 degrees with each other. The walls 42 and 44 will not lie flush against the upright surface of the floor covering after the corner has been put in place, but they will approach the plane of the wall to some extent. This is clearly indicated in FIGURE 5. The walls 52 and 44 form the outside surface of the corner member and are continuous with the lower curved portion 38. As illustrated in FIGURE 4, there may be a generally central stabilizer 45 which is located midway between the walls 42 and 44 or generally 15 bisects the angle between these walls and is positioned down at the bottom of the corner, with a part of the stabilizer 45 underlying the curved portion 38. The stabilizer 45 may be cut back, as at 46, for ease in assembly and may have barbs or the like 47 so that the 20 corner cannot be pulled out. In practice, the base member 18 will not be accurately joined at the corner and there will be space for the member 45 to be positioned between and to contact adjacent base portions. The barbs 47 may contact the edges of the base 18 to prevent withdrawal of the corner.

The inside edges of the walls 42 and 44 may have a plurality of spaced teeth 48 which have a depth approximating the thickness of the floor covering. In this way the teeth may pierce the floor covering and attach the 25 corner thereto, but do not pierce the wall proper. If the teeth were to pierce the wall it would be quite difficult to properly place the corner and drive it into position. There need not be a great number of teeth and four or so is an adequate number. Preferably the teeth 48 are 30 not in the same plane as the walls 42 and 44 but tend to converge more toward each other, as illustrated in FIGURE 5. The teeth may each have a generally horizontal upper edge 48a and a lower upwardly slanted edge 48b.

The top of the corner 30 may include a hook 50. The 35 hook 50 overlies the border member 24 and has an upper flat section 51 and a pair of downwardly extending sections 52 which extend behind the border.

FIGURES 6 and 7 illustrate the inside corner 32. The structure is substantially the same as the corner 30 except 40 that the walls converge at a different angle. Again there is a lower curved portion 54 backed up by a stabilizer 55, and a main portion 58 which extends vertically upward. The stabilizer 55 may be cut back, as at 56, and may have 45 barbs 57. At the top there is a hook 60 which has a back portion 62 adapted to extend behind the border 24. The main upright portion 58 has side walls 64 and 66 each of which have projecting teeth 68.

Considering FIGURES 8 and 9, the member 34 only 50 masks one edge of the floor covering, but spans the space between the molding 36 and the edge of the floor covering. Member 34 may include a lower curved portion 70 backed up by a stabilizer 72 and a main upright portion 74 with a hook 76 at the top. The visible slanted wall 78 has teeth 80 which are adapted to pierce the floor covering and are used in securing the member 34. Integral 55 with the wall 78 is a wall 82 which is adapted to lie flush against the molding 36 and is hidden from view once the member 34 is in position. The wall 82 may be integral 60 with the stabilizer 72 and may merely be an upward extension of the base. The teeth 80 on the inside edge of

the wall 78 are not in the same plane as the wall, but form an angle with the wall as was true with the corners 30 and 32.

The use, operation and function of the invention are as follows:

In forming the floor and wall joint as shown, the floor covering will first be laid on the floor proper after which slits will be made at the corner so that the floor covering may extend partly up along the walls and fit smoothly against the walls. The floor covering may extend two to four inches up along the walls, depending upon what would normally be used for molding. The base 18 will extend along the joint between the floor and the wall and is used to support the floor covering, for example linoleum or the like, at the joint. In this way there is a smooth curvature between the floor portion and the wall portion. The border will be attached to the wall by screws, tacks or the like and the upper edges of the floor covering will be slipped inside of the border. The corner members are then hooked over the top of the border. Next, the corners are driven into the linoleum surface to mask the opposing edge of the linoleum. Preferably a wooden tool or the like having a contour which matches that of the corner members is used in driving the teeth of the corner members into the floor covering. In this connection it is preferable that the corner members be formed of a light gauge metal, which is attractive. For example, aluminum, a light gauge steel, or possibly tin, any one of which may be chromed, is a suitable material for the corners. A different tool will be needed for each type of corner and for the edge pieces 34, however these tools are fairly simple to construct.

It is advantageous to have the lower edge of the teeth upwardly slanted as the corners are, in effect, hinged at the top by the hooks. With the teeth formed in this manner the corners will each be pulled snug against the wall and firmly held down as they are driven in.

The floor and wall joint shown and described is simple and easy to construct. By having the floor covering run up along the walls it is not necessary to use molding at the joint between the wall and the floor. In addition, the base members 18 need not be precisely and accurately cut at the corners nor mitered, as it will be covered at the corner joints by the corner members.

The invention is advantageous in that a floor can be laid without using molding at the wall joint. The floor can be quickly and easily laid and is quite attractive.

The stabilizer will extend between and contact adjacent portions of the base to prevent sidewise movement of the corner and to stabilize it. The barbs on the stabilizer will prevent removal of the corners.

Whereas the preferred form of the invention has been shown and described herein, it should be realized that there are many modifications, substitutions and alterations thereto, within the scope of the following claims.

I claim:

1. A floor and wall joint for a room including a floor undersurface and a wall surface generally at right angles thereto, a flexible floor covering on said floor undersurface and having continuous curved portions extending partly up along the wall surface, a base member extending beneath and contacting the curved portion of the floor covering between the wall and floor, said base member being split at the wall corners of the room, a border member covering the upper edge of said flexible covering adjacent the wall surface, said floor covering being slit at the wall corners of the upwardly extending portions, and a corner member overlying each slit and located at the wall corners of the room, each corner member having converging side walls and a lower curved portion extending outwardly from the corner and overlying the floor cover, said side walls gradually merging into said lower curved portion, each corner member having a hook at its upper end which overlies the border member, each corner further having a generally central lower vertical stabilizer bisecting the angle between said side walls and extending downwardly and beneath said curved portion, said stabilizer extending between the split portions of said base and contacting adjacent base portions to stabilize said corner in position and to prevent sidewise movement of said corner.

2. The structure of claim 1 further characterized in that the side walls of each corner member have a plurality of inwardly directed teeth for piercing the flexible floor covering and attaching the corner to it.

3. The structure of claim 2 further characterized in that said teeth are spaced along the inner edge of each side wall and form an angle with the side wall to which they are attached.

4. The structure of claim 2 further characterized in that said teeth are spaced, with each tooth having an upper generally horizontal surface and a lower upwardly slanting surface.

5. The structure of claim 1 further characterized by barbs on said stabilizer to prevent removal of the corner member.
